Jacob Bullock

UNITED STATES PATENT OFFICE.

JACOB BULLOCK, OF WINDSOR, NEW YORK.

IMPROVEMENT IN CARRIAGE-SPRINGS.

Specification forming part of Letters Patent No. **145,333**, dated December 9, 1873; application filed June 20, 1873.

To all whom it may concern:

Be it known that I, JACOB BULLOCK, of Windsor, in the county of Broome and State of New York, have invented a new and Improved Combination - Spring for Vehicles; and I do hereby declare that the following is a full, clear, and exact description thereof, reference being had to the accompanying drawings making part of this specification, in which—

Figure 1 is a side view of my spring applied to a buggy-body. Fig. 2 is a front elevation of the same. Fig. 3 is a top view of the spring without the body.

Similar letters of reference indicate corresponding parts in the three figures.

This invention has relation to springs for various kinds of vehicles; and it consists in a novel combination of wooden springs with steel springs, and with means for connecting them together, and also to the body-raiser or jack on which the body of the vehicle is secured, as will be hereinafter explained.

The following is a description of my invention:

In the annexed drawings, A A represent wooden springs of arched form, which are arranged parallel to each other and extend from the rear axle to the bolster G. At or near the middle of the length of these springs they are left square for the purpose of properly fitting them to the block M and steel springs C C. The four springs are firmly secured to a body-raiser or jack, D, by means of clips E or other suitable devices; and to facilitate such attach-

ment the jack D is constructed with an inverted arch at the middle of its length. The rear ends of the wooden springs A A rest upon the rear axle F, and are firmly secured thereto. The forward ends of these springs A rest upon the bolster G, and are firmly secured thereto. A few inches inside of these described bearings, near each axle, is a cross-bar, H, which is firmly secured to the wooden springs by bolts or other means. The ends of the steel springs C are suspended from the wooden springs by means of shackles i, which are located near the cross-bars H, and leave free spaces between the springs at said points of attachment. If desirable, the steel springs may be located above the wooden springs instead of below them, as I have shown in the drawings. For the purpose of affording additional strength, two diagonal braces, j j, are secured to the ends of the rear cross-bar H, and also to the rear axle. K designates a curved metal brace which surrounds and clasps the front cross-bar H, the front axle F, and the bolster G.

Having described my invention, I claim—

The wooden springs A and steel springs C, having the interposed block M and shackles i, and attached to the frame D by clips E, all combined substantially as and for the purposes described.

JACOB BULLOCK.
